UNITED STATES PATENT OFFICE.

LOUIS A. HOERR, OF ST. LOUIS, MISSOURI, ASSIGNOR TO RAILWAY DEVICES COMPANY, A CORPORATION OF MISSOURI.

ANGLE-COCK AND PIPE HOLDER.

Application filed February 8, 1924. Serial No. 691,329.

My invention relates to a combined angle cock and pipe holder and has for its object the production of a simple and effective device which will not only engage with an angle cock to prevent both rotary and longitudinal movement, but will also engage the train pipe behind the coupling. By such construction I not only strengthen the device itself by the plurality of bearing points but also protect the train pipe against flexure at the coupling, thus reducing the likelihood of leakage at this point.

In the accompanying drawings which illustrate one form of holder made in accordance with my invention, Figure 1 is a side elevation; Figure 2 is a front view, the train pipe being shown in section; and Figure 3 is a section taken on the line 3—3 of Figure 2, the train pipe and angle cock being shown in dotted lines.

5 indicates the end sill of a railway car to which my device is applied. Secured to the end sill 5, by any suitable means, such as rivets 6, is a plate 7 forming the body of the holder. One end of the plate 7 extends forwardly and downwardly at a slight angle terminating in a horizontal part 8 adapted to bear upon one of the faces of the hexagonal head 9 of the angle cock 10. Passing around the train pipe 11 adjacent to the head 9 is a U-shaped strap 12 provided with a pair of horizontal wings 13 adapted to bear against the under face of the horizontal part 8 of the plate 7. The part 8 and wings 13 are provided with aligning perforations adapted to receive threaded studs 14 preferably formed integral with a member 15. This member 15 is substantially U-shaped but is offset at 16 in the direction of the length of the train pipe 11 so as to extend forwardly a sufficient distance to engage with the recess between the body of the angle cock 10 and its head 9. The studs 14 are engaged by nuts 17 which firmly hold both the member 16 and the strap 12 in place. Said studs are preferably provided with slots 18 so that they may be spread to prevent the accidental loosening of the nuts.

The train pipe 11, as is usual, is formed of two parts secured together by a coupling 20, the forward part being commonly termed the "nipple". The part of the train pipe at

the rear of the coupling 20 is engaged by the downwardly projecting end 21 of the plate 7, which end is preferably tapered, as shown in Figure 2, and is provided with an opening 22 of the proper size to receive the pipe 11.

In applying my device to a car the opening 22 is placed over the rear end of the train pipe 11, from which the front part and the coupling 20 have been removed, after which the plate 7 is secured to the end sill and the two parts of the train pipe connected by the coupling 20. It is now only necessary to place the strap 12 and member 15 in position and screw down the nuts 17. It will be seen that my holder not only engages the train pipe at both sides of the coupling, but also engages the angle cock so as to firmly hold it in position against both rotary and longitudinal movement.

Having fully described my invention, what I claim as new and desire to secure by Letters Patent of the United States is:

1. A supporting device for the elements of a railway car consisting of a train pipe, a train pipe nipple coupled to the pipe and an angle cock carried by the nipple, which comprises a one-piece bent plate adapted to be secured to the car at a point intermediate the ends of the plate, the rear end of said plate being bent downward to support the train pipe independently of the nipple, the forward end of said plate being positioned to prevent rotation of the angle cock, and means carried by said forward end of the plate and separable therefrom and adapted to support the forward end of the train pipe nipple.

2. In a device of the class described, the combination of a plate secured to a car and having a forwardly projecting portion, a pipe clamping strap provided with wings, said plate and wings being provided with aligning perforations, angle cock retaining means comprising an offset U-shaped member and integral threaded studs passing through said perforations, and nuts engaging said studs.

In testimony whereof, I have hereunto set my hand this the 6th day of February, 1924.

LOUIS A. HOERR.
